ACETYLENE GAS GENERATOR

Fred G. Fockler, Dunn Center, N. Dak.

Application June 21, 1934, Serial No. 731,741

1 Claim. (Cl. 48—38)

The invention relates to a generator and more especially to an acetylene gas generator.

The primary object of the invention is the provision of an apparatus of this character, wherein

5 carbide held within a feed chamber can be discharged automatically or by hand into the water chamber for the generation of gas which can be utilized for welding purposes or for lighting at the option of the user of the apparatus, the latter being of novel construction whereby it can be conveniently converted either for the automatic or hand feed of the carbide for generation of acetylene gas.

Another object of the invention is the provision 15 of an apparatus of this character which is comparatively simple in construction, thoroughly reliable and efficient in its purpose, readily portable, assuring safety in the use of said apparatus, and inexpensive to manufacture.

20 With these and other objects in view, the invention consists in the features of construction, combination and arrangement of parts as will be hereinafter more fully described in detail, illustrated in the accompanying drawings, which 25 disclose the preferred embodiment of the invention, and pointed out in the claim hereunto appended.

In the accompanying drawings:

Figure 1 is an elevation of an apparatus constructed in accordance with the invention.

Figure 2 is a vertical longitudinal sectional view thereof.

Figure 3 is a sectional view on the line 3—3 of Figure 2.

35 Figure 4 is a sectional view on the line 4—4 of Figure 3.

Figure 5 is a detail plan view of the slide valve as employed in the apparatus.

Figure 6 is a vertical sectional view through 40 the strainer portion of the apparatus.

Figure 7 is a side elevation of a modified form of apparatus.

Figure 8 is a vertical sectional view there-through.

45 Figure 9 is a top plan view.

Figure 10 is a sectional view on the line 10—10 of Figure 8.

Figure 11 is a sectional view on the line 11—11 of Figure 8.

50 Figure 12 is a sectional view on the line 12—12 of Figure 8.

Figure 13 is a sectional view on the line 13—13 of Figure 8.

55 Figure 14 is a fragmentary vertical sectional view through the pressure operated brake as em-

bodied with the construction shown in Figure 8.

Similar reference characters indicate corresponding parts throughout the several views in the drawings.

Referring to the drawings in detail, particularly Figures 1 to 6 inclusive, the acetylene generator embodying the present invention comprises a cylindrical body having the separable upper and lower sections 10 and 11, respectively, these being formed with the confronting annular 10 flanges 12 through which are passed suitable fasteners 13 separably joining said sections together. The section 10 has formed interiorly thereof a hopper 14 for the reception of calcium carbide 15, while the section 11 provides a water 15 and gas chamber 16, the section 10 at its uppermost portion being formed with a filling spout 17 closed by a removable plug 18, and through this spout is introduced the carbide 15 into the hopper 14. The section 11 carries a filling spout 19 closed by a removable plug 20 and water 21 is introduced through this spout 19 into the chamber 16, as should be obvious.

Arranged within the section 10 beneath the hopper 14, which at its lowermost portion forms 25 a discharge opening 22, are transversely disposed guide tracks 23, these being arranged parallel with each other and slidably supporting a closure slide or slide valve 24 which has formed the cleats 25 to engage the tracks 23 for slidable 30 connection therewith. This slide or valve 24 is adapted to close the discharge opening 22 of the hopper 14 to shut off the feed of carbide 15 into the chamber 16 whence acetylene gas is generated for consumption.

The slide or valve 24 has formed therewith the operating stem 26 which plays through a suitable packing gland 27 on the section 10 to be extended exteriorly of the latter. This stem at its outer end carries a hand knob 28, while surrounding 40 the stem 26 within the section 10 is a coiled tensioning spring 29 which functions to urge the slide or valve 24 to a closing position, it being required to pull upon the knob 28 for the opening of the slide or valve 24, and in this open position carbide 15 will be delivered into the water 21 within the chamber 16 for the formation of acetylene gas or the generation of the same.

The section 11 carries a safety valve 30 which communicates with the chamber 16 so as to 50 relieve excess gas pressure as generated within this section 11.

The section 11 carries the oppositely disposed gas delivery pipes 31, these being fitted with gas filters 32, while extended from filters 32 are gas 55

outlet pipes 33 (only one of which is illustrated) and each of these pipes is provided with a hand operated cut-off valve 34 and having threaded outer ends 35 for the connection of an acetylene torch or a feed line of a gas lighting system.

The section 11 has fitted therewith a hand operated valved drain cock 36, so that the chamber 16 can be freed of its contents or sediment or other matter as contained therein.

- 10 In Figures 7 to 14 there is shown a modified form of the invention, wherein the lower section 37 is identical to the section 11 and carries the parts associated with said section 11, there being no variation between these sections 11 and 37.
- 15 In lieu of the section 10 there is provided the section 38 which has interiorly thereof the hopper 39, while beneath the discharge bottom of said hopper 39 is a partition 40, this having a discharge slot 41 therein, the partition being 20 removably fastened between the upper and lower sections of the body, that is, the sections 37 and 38, respectively.

Supported on the section 38 is a hanger 42 supporting a coiled spring motor 43 which, 25 through the gears 44, operates a rotatable valve shaft 45, the same being journaled vertically at the center section 38, its lower end having its bearing in the partition 40. Carried by this shaft 45 is the rotary disk-like valve 46, it having an 30 opening 47 for registration with the opening 41, these being in the path of each other so that carbide contained within the section 38 can be delivered into the section 37 for the generation of acetylene gas. The motor 43 has its spring 35 48 hand wound through the instrumentality of a gear 49 operated from a hand crank 50, the gear meshing with the gear 51 at the top of the motor 43 and joined with the winding stem 52 for the spring 48, the barrel or casing 53 of said motor 40 having a gear connection 44 with the shaft 45 to operate the same on the rotation of said barrel or casing 53, as will be apparent.

The hopper 39, at the opening 41 in the partition 40, has an overhanging protector ledge or 45 shelf 54 to prevent the gravitation of carbide within the section 38 through the openings 41 and 47 on the registering of these openings during the activity of the valve 46 or the rotation of the same.

50 Arranged on the section 38 at its top is a cylinder 55 having arranged therein its piston 56, its stem 57 being loosely connected to a brak-

ing arm 58 pivoted, at 59, to the hanger 42 and this brake arm, on movement of the piston in one direction, has a braking action on the barrel or casing 53 of the motor 43 for controlling the action of said motor. Surrounding the stem 57 5 of the piston 56 within the cylinder 55 is a coiled compression spring 60, the tension of the spring being regulated by an adjusting member 61 threaded in the end 62 of the cylinder 55, the member being formed with a wrench-engaging portion 63, so that it can be adjusted to vary the tension of the compression spring 60, and the spring normally tends to move the braking arm away from the motor. The other end of the cylinder has leading therethrough a fluid pipe 15 or conduit 64 which opens into the chamber within the section 37 and thus gas under pressure will flow through the cylinder 55 for action upon the piston 56 to operate the brake arm 58 for the braking of the motor 43 according to the 20 pressure of the gas generated within the apparatus. The gear 49 has ratchet action with a ratchet dog 65 pivotally supported by the hanger 42.

It will be apparent that in lieu of the section 10 of the body, the section 38 can be substituted and vice versa. Thus in this manner the apparatus can be converted into an automatic feed or a hand feed acetylene gas generator.

What is claimed is:

An acetylene gas generator comprising a casing having carbide and gas chambers, a disk-shaped valve operating within the carbide chamber for intermittent communication of said carbide and gas chambers with each other, a rotatable shaft for said valve, a spring-wound motor having gear connections with said shaft for operating the same, a gas pressure controlled device carried by the casing and communicating with the gas chamber for automatically regulating the motor, said device comprising a pivotally supported braking arm movable to frictionally contact with a moving part of the motor to hold said motor from turning, a piston having a stem connected with the braking arm, a cylinder for 45 the piston, a spring contacting the piston to normally influence the same to move the braking arm away from the motor, an adjustable member for tensioning the spring, and a pipe leading from the cylinder to the gas chamber. 50

FRED G. FOCKLER.
